UNITED STATES PATENT OFFICE.

EDWARD QUIRK, OF FULTON, NEW YORK.

DESIGN FOR A WEARING-PLATE FOR WAGON-REACHES.

SPECIFICATION forming part of Design No. 33,227, dated September 18, 1900.

Application filed August 13, 1900. Serial No. 26,796. Term of patent 14 years.

To all whom it may concern:

Be it known that I, EDWARD QUIRK, a citizen of the United States, residing at Fulton, in the county of Oswego and State of New York, have invented and produced a new and original Design for a Wearing-Plate for Wagon-Reaches, of which the following is a specification, reference being had to the accompanying drawing, forming a part thereof and showing a perspective view of my design.

The leading or material feature of my design for a wearing-plate for wagon-reaches, as seen in the drawing, consists of separate substantially-parallel rollers *a a* and transverse bars *b b*, uniting the rollers *a a* in the manner seen in the drawing, the ends of the rollers being mounted in the bars *b b*, said

bars being substantially flat and terminating in beaded ends at the point of union with the rollers *a a*.

The general appearance of my design is that of a rectangular parallelogram.

Having thus described my invention, what I claim, and desire to secure by Letters Patent, is—

The design for a wearing-plate for wagon-reaches as herein shown and described.

In witness whereof I have hereunto set my hand this 4th day of August, 1900.

EDWARD QUIRK.

Witnesses:

EARLE H. BENSON,

HOWARD P. DENISON.
